UNITED STATES PATENT OFFICE.

AUGUST EVALD OBERG, OF PLAINFIELD, NEW JERSEY, ASSIGNOR TO MUMFORD MOLD-
ING MACHINE COMPANY, OF PLAINFIELD, NEW JERSEY, A CORPORATION OF NEW
JERSEY.

JOLT RAMMING-MACHINE.

1,133,394.

Specification of Letters Patent. Patented Mar. 30, 1915.

Application filed August 9, 1912. Serial No. 714,258.

To all whom it may concern:

Be it known that I, AUGUST E. OBERG, a citizen of the United States, residing at Plainfield, in the county of Union and State 5 of New Jersey, have invented certain new and useful Improvements in Jolt Ramming-Machines, of which the following is a specification.

The invention relates to what are known 10 as jolt ramming machines, and particularly to the valve mechanism for controlling the reciprocating piston. The invention has for its primary objects; the provision of a valve mechanism of simple construction and positive operation; the provision of a valve so positioned as to be protected from grit and dirt, thus insuring a reliable operation; and the provision of valve mechanism so constructed that the waste of air is reduced and 15 in which a sharp positive movement of the controlling member is secured. Certain embodiments of the invention are illustrated in 20 the accompanying drawings, wherein:—

Figure 1 is a vertical section through a 25 jolt ramming machine embodying my invention, and Fig. 2 is a vertical section through a jolt ramming machine embodying a modified form of my construction.

In the construction illustrated in Figure 30 1, A is the cylinder of the apparatus carrying at the top the usual anvil B for receiving the impact of the table; C is the jolt ramming table which may be of any approved type; D is the plunger which is secured 35 to the table C and works in the cylinder A; E is the inlet port leading through the wall of the cylinder; F is the exhaust port; and G is the usual oiling device.

The plunger D is provided upon its interior 40 with the vertical valve chamber 1, such chamber being closed at its bottom by means of the screw plug 2, having the upwardly extending stem 3, upon which stem 3 the valve 4 rests when not held by air pressure in its upper position. The inlet port E communicates 45 with a groove 5 in the exterior surface of the plunger D, and this groove 5 communicates with the space at the rear of the plunger D by means of the passages 6, 7, 8 and 9. The right hand end of the passage 8 communicates with a second groove 10 in the plunger, such groove 10 being adapted to register with the exhaust port F when the plunger reaches its upper extreme of move- 50 ment, the usual packing ring being employed to prevent the passage of air to the exhaust until such ring passes the exhaust port. Communication is provided between the rear end of the valve chamber 1 and the rear end of the plunger by means of the relatively small passage 12 to the plug 2. 55

When air pressure is supplied to the apparatus through the inlet port E, the operation is as follows: Air entering through the inlet E reaches the rear end of the plunger, via 60 the groove 5 and passages 6, 7, 8 and 9, thus causing the plunger to rise. This movement is continued until the groove 10 is brought into communication with the exhaust F. Up until this time the pressure upon the 65 front and rear ends of the valve 4 is substantially the same, but as soon as the groove 10 communicates with the exhaust, there is a sudden release of pressure upon the upper end of the valve 4 due to the relatively large 70 size of the passages 7, 8, as compared with that of the passage 12, so that this valve 4 moves sharply upward as soon as the exhaust port is opened. The uncovering of 75 the exhaust occurs just after the closing of the inlet port E by the plunger, so that no air is permitted to pass directly from the inlet E to the exhaust port F, and all waste at this point is avoided. The closing of 80 the inlet and the outflowing of air to the exhaust of course results in a reduction of pressure at the rear end of the plunger so that the plunger commences to move backward substantially as soon as the exhaust is uncovered. During the downward movement 85 of the plunger, the valve 4 remains closed so that there is no additional supply of air to the rear end of the plunger during its rearward movement, the only cushioning effect being secured by reason of the air behind the plunger which does not entirely escape when the exhaust is uncovered. The valve 4 does not move down during the 90 downward movement of the plunger, as the pressure behind the valve is practically the same as that in front thereof, and the downward movement of the plunger is almost as rapid as that which the valve would have in falling. As a result, the valve remains in its upper position until the plunger is 95 brought to a sudden stop at its extreme lower position. At this time the momentum of the valve 4 in connection with the pres- 100 105

sure backed up through the passages 5, 6 and 8 causes the valve to move sharply to its lowermost position, opening the passage 5, and permitting a new charge of air to flow from the inlet port E to the rear end of the plunger. The air pressure is of course increased upon the lower side of the valve 4 during the downward movement of the plunger, by reason of the passage 12, but 10 inasmuch as this passage 12 is of much less capacity than the passages 9, 8 and 7, the pressure upon the upper end of the valve 4 is increased somewhat beyond that upon the lower end of the valve, when the plunger 15 reaches its lowermost position, so that this unbalancing of pressure operates in connection with the momentum of the valve 4 to secure a sharp, opening movement of such valve. This completes the cycle of operation. The valve 4 will thus be seen to be 20 pressure actuated to close the inlet and actuated by the jolt of the table to open the inlet.

In the modified type of construction illustrated in Fig. 2, A' is the cylinder; B' is the anvil; C' is the table; D' is the plunger; E' is the inlet port, and F' is the exhaust port communicating with the chamber H'. In this construction, the valve chamber 1' in 25 the plunger D' is provided with a valve 4' in the form of a ball and this chamber is completely closed upon its lower side by means of the screw-plug 2', having a stem 3'. The passages 7', 8' and 9' lead from the 30 upper end of the chamber 1' to the rear end of the plunger as in the other type of construction. The chamber 1' is also provided with an additional side port 13, and the 35 grooves 5' and 10' in the plunger D' correspond to the grooves 5 and 10 in the other type of apparatus.

The operation of this apparatus of Fig. 2 is as follows: When air is admitted to the port E', it passes to the rear end of the 45 plunger D' via the passages 7', 8' and 9', thus causing the plunger to move upward. This movement continues until the upper end of the groove 10' is brought into communication with the exhaust port F' at 50 which time exhaust occurs from the rear end of the plunger. During this upward movement of the plunger, the ball valve 4' occupies the position indicated in the drawing, but as soon as the exhaust is opened and as 55 soon as the passage 13 is brought into registration with the inlet valve E', the valve 4' is caused to move upward and seat by reason of the increased pressure upon its lower side, thus cutting off communication between the 60 inlet and exhaust ports and between the inlet port and the rear end of the plunger. The supply of air to the rear end of the plunger now being cut off and the exhaust being open, the plunger descends, the ball valve 4' during 65 such movement occupying its closed posi-

tion, so that there is no admission of air to the rear end of the plunger until such plunger reaches its lowermost position. When the plunger stops in its lowermost position, the momentum of the ball valve 4' causes it 70 to move to its lower position, such movement readily occurring by reason of the fact that the pressure upon opposite sides of the valve 4' is equalized, due to the backing up of pressure in the passages 9', 8' and 7' during 75 the descent of the plunger. This condition in connection with the momentum of the valve secures a sharp and effective opening movement of the valve when the plunger reaches its lower position, so that the parts 80 are in position for a repetition of the cycle as above described.

Having thus described my invention and illustrated its use, what I claim as new and desire to secure by Letters Patent is 85 the following:—

1. In combination in a jolt ramming machine, a cylinder, a piston provided with a passage therethrough leading from the side of the piston to the lower end thereof, an 90 inlet passage through the side of the cylinder adapted to register with the first passage when the piston is in its lower position, an exhaust passage through the side of the cylinder adapted to register with a portion of the first passage when the piston approaches its upper position, and a valve in the piston adapted to be closed by the unbalanced air pressure induced when the exhaust passage is brought into communication with the said passage in the piston. 95

2. In combination in a jolt ramming machine, a cylinder provided with inlet and exhaust ports, a plunger in the cylinder having a valve chamber providing communication from the inlet port to the rear end of the plunger, and a valve in the chamber arranged to permit a flow of air to the rear end of the plunger during a predetermined 105 upward movement of the plunger and to automatically cut off such flow when the exhaust port is uncovered. 110

3. In combination in a jolt ramming machine, a cylinder provided with inlet and 115 exhaust ports, a plunger in the cylinder having a valve chamber providing communication from the inlet port to the rear end of the plunger, and a valve in the chamber arranged to permit a flow of air to the rear 120 end of the plunger and to automatically cut off such flow when the exhaust port is uncovered, the said valve being arranged so as to be moved to open position by its own momentum when the piston is stopped in its downward movement. 125

4. In combination in a jolt ramming machine, a cylinder having inlet and exhaust ports, a plunger having upon its interior a vertically extending valve chamber com- 130

municating with the inlet port and with the cylinder to the rear of the plunger, and a vertically movable valve in the valve chamber arranged so as to be moved to open 5 position by its own momentum when the piston is stopped in its downward movement, and adapted to be closed by the unbalancing of the air pressure on its opposite sides induced by the opening of the 10 exhaust.

5. In combination in a jolt ramming machine, a cylinder having inlet and exhaust ports, a plunger having upon its interior a vertically extending valve chamber having 15 a connection from its front end leading to the rear of the plunger and a connection from its rear end also leading to the rear of the plunger, the said chamber having connections registering with the inlet port 20 at one extreme of movement of the plunger and with the exhaust port at the other extreme of movement of the plunger, and a valve in the valve chamber adapted to be closed by the unbalancing of the air pressure 25 on its opposite sides induced by the uncovering of the exhaust port, and arranged so as to remain closed cutting off the supply of air to the rear of the plunger until the plunger reaches its lower position. 30

6. In combination in a jolt ramming machine, a cylinder having inlet and exhaust ports, a plunger having upon its interior a vertically extending valve chamber having 35 a connection from its front end leading to the rear of the plunger and a connection of smaller area from its rear end also leading to the rear of the plunger, the said chamber having connections registering with the 40 inlet port at one extreme of movement of the plunger and with the exhaust port at the other extreme of movement of the plunger, and a valve in the valve chamber adapted to be closed by the unbal- 45 ancing of the air pressure on its opposite sides induced by the uncovering of the exhaust port, and arranged so as to remain closed cutting off the supply of air to the

rear of the plunger until the plunger reaches its lower position.

7. In combination with a jolt ramming machine, a cylinder, a piston provided with a passage leading from the side of the piston to the lower end thereof, an inlet passage through the side of the cylinder and a valve in the piston arranged to control the flow of air to the lower end of the piston, said valve being pressure-actuated to cut off the flow of air after the piston is moved a predetermined distance upward and being closed by its own momentum on downward movement of the piston. 50 55 60

8. In combination in a jolt ramming machine, a cylinder, a plunger provided upon its interior with a vertical valve chamber 65 and a valve in the chamber for controlling the flow of air to the lower side of the plunger, said valve being held in open position by fluid pressure during a predetermined upward movement of the plunger and automatically closed upon reduction of pressure and adapted to be moved to open position by its own momentum when the plunger is stopped in its downward movement. 70

9. In combination in a jolt ramming machine, a cylinder provided with inlet and exhaust ports, a plunger in the cylinder having a valve chamber providing communication from the inlet port to the rear end of the plunger, and a valve in the chamber 80 arranged to permit a flow of air to the lower end of the plunger during a predetermined upward movement of the plunger and to automatically cut off such flow when the exhaust port is uncovered, said valve being 85 moved to open position by its own momentum when the plunger returns to lower position. 75

In testimony whereof I have hereunto signed my name in the presence of the two 90 subscribed witnesses.
